UNITED STATES PATENT OFFICE.

ULYSSES G. LEEDY, OF INDIANAPOLIS, INDIANA, ASSIGNOR TO LEEDY MANUFACTURING COMPANY, OF INDIANAPOLIS, INDIANA, A CORPORATION OF INDIANA.

SNARE-DRUM STICK.

Application filed January 22, 1923. Serial No. 614,156.

To all whom it may concern:

Be it known that I, ULYSSES G. LEEDY, a citizen of the United States, residing at Indianapolis, in the county of Marion and State of Indiana, have invented a new and useful Snare-Drum Stick, of which the following is a specification.

My invention relates to improvements in drum sticks for snare drums. It has for one of its objects that of producing a drum stick for snare drums which, while having all of the advantages of the conventional, hard headed snare drum stick in playing the snare drum, will possess added advantages for use in playing the various instruments on which the snare drummer performs in orchestra work.

As is well known, the snare drummer of an orchestra uses his drum sticks, not only for playing the snare drum, but also for striking the various bells, tambourines, toms, wood blocks and other devices. When these instruments are struck by the usual hard headed drum stick a clashing or unmusical note is produced. It is desirable that these devices be struck with a padded beater. Heretofore this has been impractical because during the performance it would be impractical for the snare drummer to put down his snare drum stick and pick up a padded beater and the padding of the snare drum stick would so interfere with the proper balance of the stick that proper performance on the snare drum would be prevented. As is well known, snare drum sticks have to be carefully manufactured and carefully balanced, the weight of the head has to bear a definite relation to that of the handle so that the balance of the stick will be preserved throughout and a destruction of this balance materially interferes with the artistic performance of the drummer upon the snare drum.

For this reason, while the desirability of a padded head has been appreciated, heretofore no attempt has been made to pad the head of the snare drum stick for the very reason that it would destroy the balance of the stick.

My invention is primarily designed to provide a snare drum stick having the advantages of a perfectly balanced stick for playing the snare drum and providing at the same time, a soft head.

For the purpose of disclosing my inven-

tion I have illustrated one embodiment thereof in the accompanying drawing in which—

Fig. 1 is a side elevation of my improved form of snare drum stick;

Fig. 2 is a perspective view of one type of snare drum for which the stick is designed, and

Fig. 3 is a sectional view through the stick head.

In the embodiment illustrated, the drum stick 1 is of the conventional type of stick having the handle 2. In place of the conventional type of head of the usual snare drum stick I substitute a soft head. In providing this type of head I preferably turn a spindle 4 on the stick at the end where the usual head is provided and mount on this spindle a rounded felt head 5. This felt head is fairly hard and in constructing this head the weight is very carefully adjusted to maintain the same balance that would be provided on the stick in event the usual wooden head is provided. One way of maintaining this balance is to have the weight of the felt equal to the weight of the wood which would be allowed to remain on the spindle in event the conventional wooden headed stick were used. By such a construction I am enabled to maintain the accurate balance of the stick and at the same time provide a soft head for striking the various instruments on which the snare drummer performs. Furthermore, the felt head as provided in no way interferes with the note produced by the drum nor with the playing of the drum by the performer.

I claim as my invention:

A snare drum stick of conventional size and shape and having a felted beater head of a weight equivalent to the conventional wooden head for the same size and balanced stick to produce a soft beater head on a snare drum stick whereby the stick may be used for performance on other instruments than the drum without sacrificing the correct balance of the stick for snare drum performance.

It witness whereof I, ULYSSES G. LEEDY, have hereunto set my hand at Indianapolis, Indiana, this 10th day of January, A. D. one thousand nine hundred and twenty three.

ULYSSES G. LEEDY.
